UNITED STATES PATENT OFFICE.

MAX GLASS, OF VIENNA, AUSTRIA-HUNGARY.

DOUBLE-WALLED EXPLODING PROJECTILE.

965,812.

Specification of Letters Patent. Patented July 26, 1910.

Application filed November 22, 1909. Serial No. 529,408.

To all whom it may concern:

Be it known that I, MAX GLASS, a subject of the Emperor of Austria-Hungary, and a resident of 176 Hadikgasse, Vienna, Austria-Hungary, have invented certain new and useful Improvements in Double-Walled Exploding Projectiles; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The subject-matter of this invention is a double-walled exploding projectile, in which a specially large chamber for receiving an explosive is made by means of two concentric cylinders. The point is attached specially, so that it can be given the desired required degree of hardness at its inner and outer faces in simple manner. The double walls are made by a specially inserted tube, so that the envelop or coating, cast integral with the bottom or pressed out of steel, may be made comparatively thin. When assembling the projectile the position of its center of gravity can be placed where it is most advantageous corresponding to the intended use of the projectile.

One illustrative embodiment of the invention is represented by way of example in the accompanying drawing, wherein:

Figure 1 is a longitudinal section, and Fig. 2 a cross section in the plane A—B in Fig. 1 through the projectile. Fig. 3 is a perspective of a particular type of explosive filling; Fig. 4 is a perspective of a segment of the filling shown in Fig. 3; and Fig. 5 is a perspective of the segment (Fig. 4) showing its elements separated.

Referring to the drawing, the projectile comprises a cylinder or envelop *a* made integral with the bottom *b*. This cylinder carries in known manner the guide ring *c* for the gas-tight closure. In the bottom *b* is screwed centrally a tube *d* whose section is such that this tube in combination with cylinder *a* has the required cross-sectional area so that, when impacting, the projectile possesses the necessary strength and capability of penetration. The point *f* of the projectile may be screwed on tube *d* and simultaneously abut against cylinder *a*, but, if preferred, a ring *h* provided with a guide

ring *g* may be inserted between these two parts, as shown. The tapered part of the projectile may consist of one special part forming the point of the projectile.

The interior of tube *d* and the recess in the point of the projectile, also chamber *k* between tube *d* and cylinder *a* serve for holding the explosive.

The projectile is preferably filled through a hole in the bottom. Holes *i* in tube *d* enable the explosive to enter into the annular chamber *k*.

The above described projectile can be adapted to all kinds of projectiles, as the same meets all preliminary conditions affecting an explosive projectile, such as the possibility of accommodating a large explosive charge and great divisibility of the projectile. Also, the same may be utilized as armor-piercing shell with the highest degree of destructibility. To this end, chamber *k* may be filled with a cylindrical briquet *m* formed of segments of rings *n* and *o* held together by means of an organic or inorganic binding agent. The segments are assembled into complete rings and each ring may consist, for example, of two layers of triangular superposed parts whose slanting sides touch one another so that the superposed parts form a rectangle in section (see Figs. 4 and 5). Further, only the bottom portions of chamber *k* and the interior of tube *d* may be filled with explosive charge, whereupon this charge is covered over and the upper part filled with small parts connected by briquetting. The ignition is adapted to the purpose for which the projectile is used.

If the projectile is to be filled with explosive and very sensitive preparations, such a preparation will always be placed in the central tube, whereas in chamber *k* will be placed a filling which absorbs the preparation and acts as an insulating medium for the central filling. If desired, to this end a less sensitive preparation may be employed for insulating in chamber *k*.

Obviously the briquetting shown in Figs. 3, 4 and 5 may be adapted for the purpose to which the projectile is to be put. Thus in the examples supposed, when it is to serve as shrapnel, the segments *n* and *o* may be merely projectile non-explosive elements. On the other hand if the projectile is to be employed as a torpedo where the highest possible explosive effect is sought, the briquetting may be of explosive nature. Again

it may be porous, whether explosive or non-explosive, and thus serve to absorb a liquid explosive introduced into the inner chamber; so that if initially non-explosive, the briquets may become highly explosive after they have absorbed said liquid. Again portion of the briquetting may be explosive and portion non-explosive, thus combining the explosive and projectile elements.

10 I claim:

1. A double walled explosive projectile having a heavy base with threaded recess, a relatively light tubular outer shell integral with said base, an independent point having a threaded recess in combination with a relatively heavy connecting tube screwed into the recesses in said base and point, said tube serving to take up the greater portion of the stress of firing and impact, and forming an outer chamber between said tube and shell and an inner chamber within the tube, substantially as described.
2. A double walled explosive projectile having a heavy base with threaded recess, a relatively light tubular outer shell integral with said base, an independent point having a threaded recess, in combination with a relatively heavy perforated connecting tube screwed into the recesses in said base and point, said tube serving to take up the greater portion of the stress of firing and impact, and forming an outer chamber between said tube and shell and an inner chamber within the tube with which said outer chamber communicates through said perforations, substantially as described.

3. A double walled explosive projectile having a heavy base with threaded recess, a relatively light tubular outer shell integral with said base, an independent point having a threaded recess, in combination with a relatively heavy connecting tube screwed into the recesses in said base and point, said tube serving to take up the greater portion of the stress of firing and impact, and forming an outer chamber between said tube and shell, and an inner chamber within the tube, together with a flanged guide ring clamped between said point and shell, substantially as described.

4. A double walled explosive projectile having a heavy base with threaded recess, a relatively light tubular outer shell integral with said base, an independent point having a threaded recess, in combination with a relatively heavy connecting tube screwed into the recesses in said base and point, said tube serving to take up the greater portion of the stress of firing and impact, and forming an outer chamber between said tube and shell, and an inner chamber within the tube, together with a filling for said outer chamber comprising a plurality of rings of segments shaped to fit each other and to conform to the curvature of said chamber.

In testimony whereof I have signed my name to this specification, in the presence of two subscribing witnesses.

MAX GLASS.
